INVENTOR:

Frank E. Morris,
By Wm. Wallace White
ATTY.

UNITED STATES PATENT OFFICE.

FRANK EDWARD MORRISS, OF LONDON, ENGLAND.

WIND-SCREEN.

1,393,239.

Specification of Letters Patent. Patented Oct. 11, 1921.

Application filed January 7, 1920. Serial No. 349,998.

To all whom it may concern:

Be it known that I, FRANK EDWARD MORRISS, of London, England, a subject of the King of Great Britain and Ireland, have 5 invented certain new and useful Improvements in or Relating to Wind-Screens, of which the following is a specification.

This invention relates to screens for motor vehicles of the type in which the standard 10 is formed of telescopic tubes, the screen being so mounted that the upper screen slides in front of the lower screen, the screen being adapted to be moved up and down by a rack or similar device.

15 The object of this invention is to provide an improved screen of this type.

A screen made in accordance with this invention is characterized in that the glass is let into grooves in flanges integral with 20 the standard and sliding tubes.

Means may be provided for raising the sliding members simultaneously.

Referring to the drawings filed here- 25 with:

Figure 1 is an elevation of one form of screen made in accordance with this invention;

Fig. 2 is a section to a larger scale of the sliding member on line 2, 2, Fig. 1.

30 Fig. 3 is a section to a larger scale of the sliding member and fixed post on line 3, 3, Fig. 1.

Fig. 4 is a sectional elevation showing the rack.

35 *a a* are a pair of hollow posts adapted to be secured to the car; *b b* are a pair of sliding members adapted to slide in the posts *a a*. On each post *a a* is mounted a socket *c* adapted to receive and support a sheet of 40 glass *d*.

On each sliding member *b b* is mounted a socket *e* adapted to hold a sheet of glass *f* referred to hereinafter as the sliding member. Between the fixed posts is a shaft *g*

carrying two pinions *h h* adapted to engage 45 with racks formed on the lower parts of the sliding members. On the shaft *g* is a milled wheel *j* by which it may be turned. The glass *f* is adapted to slide in front of the glass *d*.

In use the sliding member may be raised and lowered by operating the milled head or wheel *j*. Springs or other catches or stops may be provided to secure the sliding part in any desired position.

With the screen made in accordance with this invention any rain striking the glass cannot be blown between the upper and lower parts as is frequently the case with screens as generally constructed. Any 60 shape of glass can be used and the screen so made is entirely draft and rainproof.

What I desire to secure by Letters Patent is:—

A screen for motor vehicles, comprising a 65 pair of hollow tubular posts or standards adapted to be secured to the vehicle, a pair of sliding tubular members adapted to fit slidably in the said tubular posts and to be supported and guided thereby along the 70 whole length engaging the said posts, said posts and sliding members being each provided with a grooved longitudinal flange on the inner side adapted to receive and support a sheet of glass, the flanges on the said 75 sliding members being adapted to engage longitudinal slots in the said posts, a rack on each said sliding member, a bracket on each of said posts, a pinion on said bracket adapted to engage said rack, a common axle 80 for both said pinions and a milled head on said axle adapted to operate simultaneously both of said sliding members so that the sheet of glass therebetween may be adjustable vertically in position.

In testimony whereof I have signed my name to this specification.

FRANK EDWARD MORRISS.
